US0D1076394S

(12) **United States Design Patent** (10) **Patent No.:** **US D1,076,394 S**
(45) **Date of Patent:** **** May 27, 2025**

(54) **SHOE UPPER**

(71) Applicant: **Skechers U.S.A., Inc. II**, Manhattan Beach, CA (US)

(72) Inventor: **Jung Kim**, Gardena, CA (US)

(73) Assignee: **Skechers U.S.A., Inc. II**, Manhattan Beach, CA (US)

(**) Term: **15 Years**

(21) Appl. No.: **29/939,385**

(22) Filed: **Apr. 26, 2024**

Related U.S. Application Data

(63) Continuation of application No. 29/932,952, filed on Mar. 15, 2024, now Pat. No. Des. 1,047,364.

CLAIM

The ornamental design for a shoe upper as shown and described.

DESCRIPTION

FIG. 1 is a front perspective view of a shoe upper in accordance with my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The dash-dash broken lines shown in the drawings represent environmental structure of the shoe and form no part of the claimed design. The dot-dash broken lines define the bounds of the claimed design and form no part thereof.

1 Claim, 7 Drawing Sheets
